B. AMES ET AL

ELECTRIC HORN

Filed Jan. 9, 1922

UNITED STATES PATENT OFFICE.

BUTLER AMES AND PHILIP J. GILINSON, OF LOWELL, MASSACHUSETTS, ASSIGNEES
TO HEINZE ELECTRIC COMPANY, OF LOWELL, MASSACHUSETTS, A CORPORATION
OF MAINE.

ELECTRIC HORN.

Application filed January 9, 1922. Serial No. 527,991.

This invention relates to signal horns of the electrically operated diaphragm type, particularly adapted to be used upon motor vehicles to give timely warning of their approach.

- In order to be acceptable to the trade, a device of this character should be compact in form, light in weight, of substantial and durable construction, relatively low in first cost and upkeep, should be reliable and unfailing in operation, and should emit a signal tone of pleasing character. While numerous attempts have been made to improve such devices, any changes made with the purpose of bettering such a device in one particular, have commonly resulted injuriously as respects other parts or properties of the device. This is particularly true when changes for the purpose of cheapening the device or making it more compact or light in weight have been attempted, as in most such cases the sound emitted by the horn has been made raucous and unpleasant thereby rendering the horn of little commercial value.
- In order to produce a true musical tone, it is essential that the striker vibrate with a predetermined velocity and amplitude. Any looseness or play between the supporting parts or any failure of the circuit breaker properly to function leads however, to the production of a confused noise having little carrying power and of decidedly disagreeable acoustic quality. For best results moreover, the natural period of vibration of the vibrating parts should approximate that of the diaphragm and when attempts have been made heretofore to devise signals of compact form, this feature has been sacrificed altogether.
- The principal objects of the present invention are accordingly, to provide a signal of compact and durable type, light in weight and simple of construction, while at the same time providing rigid supporting means for the movable parts whereby the action of the latter may accurately be predetermined,—so constructed as to permit of the employment of a striker supporting spring having the desired amplitude of vibration, and employing electrical contact elements capable of accurate adjustment. In accordance with the present invention the above objects are attained by providing a base

plate or cover for the diaphragm and securing directly to said base plate, or to a frame fixedly secured thereon, all the various parts of the operating mechanism. Preferably the frame referred to comprises oppositely diverging arms to the outer ends of which the armature supporting spring is secured. This arrangement permits of the employment of a spring of a length substantially equal to the diameter of the diaphragm and by properly determining the resiliency of such spring an amplitude of vibration substantially equal to that of the diaphragm may be readily attained. The armature and striker are rigidly secured to such spring, the striker however, being adjustable to permit of determining its initial position as respects the diaphragm. The contact making and breaking devices are carried upon a bracket integrally secured to the base plate and such contact making and breaking devices are arranged for relative adjustment whereby great accuracy in operation may be attained. Suitable securing means are provided whereby undesirable relative movement of parts may be eliminated, the whole device being of a very simple construction and cheap to manufacture. In securing the supporting frame to the base plate, advantage is taken of the presence of the magnet cores, which are extended through openings in the frame and base plate and are headed over on the under side of the latter. The base plate, frame, and magnets are thus rigidly and permanently connected so that no looseness can develop between these parts. The movement of the armature through its predetermined path is thus substantially assured and although most of the parts, including the base plate and frame are made from sheet metal stampings, the signal is sufficiently rigid to withstand rough usage and the vibration and shocks to which a device of this character is commonly subjected.

In the accompanying drawings there is illustrated by way of example, a preferred embodiment of the device whereby the above objects may be attained, and in such drawings,—

Fig. 1 is an end elevation with the cap removed to show the interior mechanism;

Fig. 2 is a section on the line 2—2 of Fig. 1;

Fig. 3 is a section on the line 3—3 of Fig. 1;

Fig. 4 is a perspective view of a clip for holding the armature;

5 Figs. 5 and 6 are, respectively, side and end elevations of one of the contact members; and

Fig. 7 is a perspective view of the other contact member.

10 The embodiment of the invention shown for the purpose of illustration is an electrically operated signal comprising a horn 8 which is expanded at the rear and provided with a circumferential flange 9 defining a recess in which are received a diaphragm 10 and a base plate 11, the latter being spaced from the diaphragm by an annular washer 10^a. These parts are preferably permanently united in any suitable manner, as by rivets 13^a and bolts 14^a. Certain of the bolts and rivets pass through a bracket 15^a by which the signal is conveniently mounted upon a vehicle. The base plate 11 is outwardly dished to a slight extent to space the central portion thereof from the diaphragm a greater distance than is provided by the annular washer 10^a. Mounted upon plate 11 is a U-shaped frame 12 comprising outwardly inclined arms 13, provided with outwardly directed end portions 14 disposed substantially in the same plane. Upon the members 14 is mounted, by means of clips 15 and screws 16, an elongate, laminated, flat spring 17, comprised of a plurality of strips of metal such for example as spring steel, said spring being of a length approximately the effective diameter of the diaphragm. Preferably the length of the spring and the number and resilience of the laminæ comprising it is so chosen that the natural period of oscillation of the vibrating parts is substantially equal to that of the diaphragm. Attached to the under side of spring 17 is an elongate armature 18 also laminated, if desired, and held fast on the spring by means of hammer or striker rod 19, the threaded end of which is received in a threaded opening in the armature, which, in turn, is held tightly engaged with the spring by a nut 20 on the projecting end of the striker rod. Between armature 18 and spring 17 is a clip 21 shown in perspective in Fig. 4 having a central opening 22 through which striker 19 passes and integral off-set portions 23 adapted to embrace the laminated armature as indicated in Fig. 3, the clip also having oppositely off-set portions 24 between which spring 17 is received. The function of the clip 21 is to hold armature 18 always in parallel disposition with respect to spring 17.

By means of the cut or slot 25 in the top of striker rod 19, the latter may be adjusted relatively to the spring and the armature. 65 This is accomplished by loosening nut 20

and then turning striker rod 19 the required amount by means of a screw driver or other suitable tool inserted in slot 25.

Striker 19 as shown extends downwardly between electro-magnets 26 and through openings in both frame 12 and plate 11 as indicated in Fig. 3 with its free end closely adjacent to but normally out of contact with the diaphragm 10. Electro-magnets 26 rest upon the frame 12, their cores passing through aligned openings in the frame and base plate and being headed over beneath the latter as indicated at 27, or otherwise suitably made fast in said plate to permanently unite the frame and the base plate.

70 Means for producing make-and-break electrical connection through the magnets, preferably comprises a pair of contact members 75 adjustably supported upon a member 28 preferably integral with base 11 and offset therefrom (Figs. 1 and 3). The upper contact member is supported in proper position by a bracket 29 (Figs. 5 and 6), having a main portion of generally rectangular form having a centrally disposed elongate slot 30. An extension 31 is provided at one side of 80 said bracket, and lying in the plane thereof, such extension having an arm 31^a extending first upwardly and then outwardly at substantially 90° as indicated at 32, the last 85 named member extending laterally as shown at 33 in a direction substantially parallel to the plane of bracket 29, which disposes the contact point 34 in a plane perpendicular to 90 and substantially axial of the slot 30.

95 The lower contact member is supported by an angular bracket 35 having an elongate slot 36 similar to slot 30 of the upper member and provided with a flat spring 37 riveted as at 38 or otherwise suitably fast upon its horizontal portion. Upon the free end of spring 37 is fixed a contact point 39 so disposed that when angular supports 29 and 35 are properly adjusted upon the extension 100 28, contact points 34 and 39 are in a vertical aligned disposition as shown in Fig. 3. The free end 37^a of spring 37 extends under armature 18 so that when the latter is pulled downwardly by the action of magnets 26, the armature strikes spring 37 and breaks the contact between points 34 and 39. Brackets 29 and 35 are separated from each other and from the supporting member 28 by suitable plates 40 of insulating material and are clamped in adjusted position by screws 41.

105 The entire mechanism is protected from dust and moisture by a cover 42 which has on offset annular flange fitting in the space between flange 9 of the horn and the rim of base plate 11, being retained in position by nuts 43 on the projecting threaded ends of bolts 14^a. The electric circuit through the device includes a suitable source of power (not shown), binding post 44 (Fig. 1), conductor 45, electromagnets 26 which are con- 115

nected in series, conductor 46 (Figs. 1 and 3) which is attached to projection 31 of contact member 29, contact point 34, contact point 39, bracket 35, screws 41 to support 28 and ground. Slot 30 in bracket 29 is not only sufficiently large to permit adjustment of this member both vertically and horizontally, but also prevents contact of such member with screws 41, whereby short circuiting 10 of the device is prevented. Slots 30 and 31 permit individual adjustment in two dimensions of each of brackets 29 and 35 by slightly loosening screws 41, and adjustment in the third dimension is possible when 15 necessary by using insulating plates 40 of different thickness.

The diverging inclination of arms 13 of U-shaped frame 12 permits the use of spring 17 of proper length to provide for the 20 desired amplitude of vibration of the hammer under the vibrating influence imparted by the action of the magnets and the production of a pleasing tone with a minimum expenditure of energy. By using a multiple 25 or laminated spring greater flexibility may be secured than with a single spring and thus by using a greater or lesser number of laminae, great nicety in adjustment of the amplitude of vibration may be obtained. At 30 the same time, such a spring insures practical immunity from breakage.

The herein disclosed mechanism requires no lubrication whatever and but little if any 35 adjustment of either the hammer or the contact points. No special mechanical or electrical knowledge is required to make either of such adjustments if necessary, while the rigid support afforded by the base plate and frame makes it possible to obtain uniform 40 tone production throughout the life of the mechanism.

Having thus described the invention in a specific embodiment of the same, together 45 with the mode of operation thereof, what we claim and desire to secure by Letters Patent of the United States is:—

1. A device of the character described 50 including a diaphragm, a base plate adjacent the diaphragm but spaced therefrom, a vibrating striker and operating mechanism therefor secured to said base plate, said base plate having an aperture therein through which the striking mechanism operates, and said base plate further having a portion cut 55 therefrom and bent up substantially at right angles thereto adjacent the striker mechanism, said bent-up portion forming a supporting bracket for a pair of supplemental brackets, one of said supplemental brackets 60 bearing a stationary contact and the other of said supplemental brackets bearing a vibrating contact having a portion projecting into the path of movement of the striker mechanism.

2. A device of the character described

including a base plate, a supporting bracket carried thereby and a pair of supplemental brackets mounted on the supporting bracket, one of said supplemental brackets having an inwardly deflected portion bearing a contact 70 and the other of said supplemental brackets having an outwardly deflected portion extending in the opposite direction from the deflected portion of the first bracket and having secured thereto a vibrator extending 75 inwardly toward the first bracket and provided with a contact for cooperation with the contact on the bent portion of said first bracket.

3. A device of the character described 80 including a base plate, a supporting bracket carried thereby and a pair of supplemental brackets mounted on the supporting bracket, one of said supplemental brackets having an inwardly deflected portion bearing a contact 85 and the other of said supplemental brackets having an outwardly deflected portion extending in the opposite direction from the deflected portion of the first bracket and having secured thereto a vibrator extending 90 inwardly toward the first bracket and provided with a contact for cooperation with the contact on the bent portion of said first bracket, said base plate having an electrically actuated vibratory striking mechanism 95 mounted thereon immediately adjacent the bracket and the vibrator having a projection extending into the path of movement of said striking mechanism.

4. In a device of the character described, 100 a base plate bearing electrically operated vibratory striker mechanism, said base plate having a bracket rising therefrom immediately adjacent said striker mechanism, a supplemental bracket carried by the main 105 bracket and longitudinally adjustable with respect thereto and having a portion extending inwardly toward the striker mechanism and a second supplemental bracket carried by the main bracket and having a portion 110 extending away from the striker mechanism, said outwardly extending portion having a vibrator secured thereto and extending inwardly past the first bracket into the path 115 of movement of the striker mechanism, said supplemental brackets being insulated one from the other and being provided with cooperating contacts, both of said supplemental brackets having corresponding elongated slots formed therein, and common fastening devices for securing both supplemental brackets to the main supporting bracket whereby the brackets may be simultaneously adjusted to vary the point at 120 which the projection will be engaged by the vibrating striker mechanism and may be relatively adjusted to vary the tension of the vibrator.

5. A contact-bearing bracket for an electric horn in the form of a plate having a 130

relatively wide elongated slot formed therein, said plate having an upward extension terminating in an inwardly bent L-shaped portion having an electric contact at its terminus, substantially as illustrated.

5 6. In a device of the class described an elongate spring, a magnet, an armature carried by said spring for cooperation with said magnet, and means for alternately 10 making and breaking a circuit through said magnet comprising points normally in contact, one of said points being mounted upon a spring extending into the path of movement of said armature as it approaches 15 the magnet whereby contact between said points is broken upon such movement of the armature, and means whereby each of said points may be adjusted in two dimensions.

20 7. In a device of the class described an elongate spring, a magnet, an armature secured to said spring and cooperable with said magnet, and means for alternately 25 making and breaking a circuit through said magnet comprising points normally in contact, one of said points being resiliently mounted, an element movable with said last named contact and extending into the path of movement of the armature whereby 30 contact between said points is broken on the movement of the armature toward the magnet, and means whereby either of said points may be adjusted in either of two dimensions, such means including slotted 35 brackets for supporting said points.

8. In a device of the class described an elongate spring, an electro-magnet, an armature secured to said spring and cooperable with said magnet, and means for alternately 40 making and breaking a circuit through said magnet comprising points normally in contact, one of said points being mounted upon a spring having an element thereof extending into the path of 45 movement of said armature whereby contact between said points is broken on the movement of the armature, toward the magnet, and means whereby either of said points may be adjusted in three dimensions, said 50 means including angular brackets supporting said points, such brackets having elongated slots therein, spacers between said brackets, and means passing through said

slots for securing the brackets to a fixed support.

9. A bracket for use in connection with the contact mechanism of an electric horn comprising an angle plate having a relatively wide elongated slot formed in one leg and having a vibrator secured to the 60 outer portion of the other leg, the intermediate portion of said other leg being formed with an ogee bend to provide clearance for the vibrator, said vibrator extending an appreciable distance to the opposite 65 side of the slotted portion of the plate from that to which the leg projects, substantially as illustrated.

10. An adjustable contact breaker mechanism for electric horns including a support 70 and a pair of brackets adjustably mounted thereon, one of said brackets comprising a plate member having a relatively wide elongated slot formed therein and having a terminal portion bent at right angles thereto, said bent portion being of L-shaped formation to bring its terminus substantially 75 in line with the slotted portion of the plate but laterally displaced with respect thereto, a second bracket portion having a similar 80 wide elongated slot formed therein, said second bracket portion having an outwardly extending end and having secured to said end a vibrator extending inwardly past the two slotted portions of the brackets, 85 the termini of the L portion of one bracket and of the vibrator of the other bracket being provided with contact points for co-operation one with the other, and fastening devices carried by the main supporting 90 bracket and of less diameter than the width of the slots and spaced nearer together than the length of the slots, said fastening devices passing through the slots of the brackets and clampingly securing the parts 95 in position while the excess in width over the dimensions and arrangement of the fastening devices permits of simultaneous adjustment of the two supplemental brackets as a unit or relative longitudinally or 100 transverse independent adjustment thereof, as described.

Signed by us at Lowell, Massachusetts, this fourth day of January, 1922.

BUTLER AMES.
PHILIP J. GILINSON.
